UNITED STATES PATENT OFFICE.

ROCCO PRONINI, OF SMITH RIVER, CALIFORNIA.

LOCK SPIKE.

Application filed February 18, 1926. Serial No. 89,199.

This invention relates to improvements in spikes.

The primary object of this invention is the provision of a lock spike preferably adapted for use in connection with railway work, but which is susceptible of other uses; the same embodying a novel pawl means to effect its retention on the road bed against accidental withdrawal.

10 A further object of this invention is the provision of an improved tie plate and lock spike construction for the retaining of rails on ties and a road bed.

15 A further object of this invention is the provision of an improved spike construction embodying novel means to guard the driving of the spike, and including novel detent means to prevent accidental withdrawal of the spike.

20 Other objects and advantages of this invention will be apparent during the course of the following detailed description.

In the accompanying drawing, forming a part of this specification, and wherein similar reference characters designate corresponding parts throughout the several views,

25 Figure 1 is a fragmentary cross sectional view showing the improved spike, in relation to a novel type of bed plate for the retention of a rail upon the bed plate, and upon a tie, to prevent the withdrawal of the spike with respect to the tie.

30 Figure 2 is a plan view, partly in section, of the application of the improved spike.

35 Figure 3 is a sectional view taken substantially on the line 3—3 of Figure 1, below the bed plate of the spike, looking upwardly.

40 Figure 4 is a side elevation partly in section, showing the improved spike and its detent means.

45 Figure 5 is a view, partly in section, of the improved spike, taken at right angles to the view illustrated in Figure 4.

Figure 6 is a bottom plan view of the improved spike and associating details.

50 In the drawing, wherein for the purpose of illustration is shown only a preferred embodiment of this invention, the letter A may generally designate the improved lock spike which is adapted for use in the retaining of rail sections B, upon a novel type of bed plate C, in supported relation upon ties D; a wedge member E being used in a novel relation with the lock spike A to maintain it 55 in locked position with respect to the tie and bed plate, against accidental withdrawal.

Referring to the spike A, the same includes a tie inserting shank 10, having a head 11 at the top thereof, with the rail base engaging flange 12 extending laterally of one side surface 13 of the shank 10, in the usual relation. The shank 13 at the lower end thereof has a tapered or pointed end 14, the inner and outer surfaces of the shank 10 at the lower end tapering to a chisel edge 15, in the usual relation. The pointed end of the shank 13 is novel in this respect, that the tapered inner and outer surfaces thereof are each provided with a substantially vertically disposed guide extension 17, which provides 60 outer edges tapering from their upper ends to a point at the lower ends thereof, as illustrated in Figure 5 of the drawing; these ribs decreasing in projection from the lower ends to the upper ends thereof where they merge 65 into the body of the shank, as illustrated in the drawing. The ribs 17 are provided at opposite sides of the lower pointed end of the shank, at diagonally opposed corners of the shank, and they assist materially in the 70 straight line driving and removal of the straight shanks with respect to the tie.

The shank 13 is preferably provided with a transverse opening 20 extending entirely transversely of the shank from the inner 75 to the outer sides thereof, within which a locking dog or pawl 25 movable operates in a novel relation. The pawl or dog 25 at its lower end is provided with an apertured pivot extension 26, adapted to receive a 80 pin 27 therethrough for pivoting the pawl or detent in the lower end of the opening 20, between the inner and outer side surfaces of the shank 10. To receive this pivoted extension 26 the opening 20 is recessed 85 at 28. From the pivot extension 26 the detent body tapers at an increasing width towards the upper edges thereof; the inner and outer side edges 29 and 30 diverging 90 from the pivot 27. The slot or opening 20, 100 of the shank 10 is of uniform width, to accommodate the pawl or detent 25, which is preferably flat and of uniform thickness, as illustrated in the drawing. The lower portion of the slot or opening 20 is provided 105 with a shoulder 35 diagonally sloping upwardly from the pivot recess 28 towards the outer side 36 of the spike shank 10 against which the sloping edge 30 of the detent 25 may abut, when the detent 25 is projecting 110 entirely to the outer side 36 of the shank 10, as illustrated in Figure 4 of the drawing.

In this relation of parts, it is to be particularly noted that the detent at its opposite side does not project from the side 13 of the shank 10, and thus offers no detent projection below the head 12. The pawl member 26 upwardly from the upper edge 40 of the body thereof is provided with an extension 41, considerably less in width than the width of the portion of the detent therebelow, adapted to abut against a shoulder 42 formed inwardly of the outer side 36 of the shank 10, in order to limit the extent to which the lock or pawl side 44 of the detent 25 may extend from the side 13 of the shank 10. Inwardly of the top edge of this extension 41 a groove 45 is formed, to facilitate insertion of a tool in order to withdraw the detent lug portion 44 when desiring to remove the spike.

Referring to the construction of the tie plate C, the same is of the type adapted to rest upon the tie D beneath the base of the rail B. It is provided with suitable openings 50 therethrough adapted to receive the polygonal shanks 10 of the spike A. Inwardly of the bottom surface 51 of the tie plate C, a recess 52 is provided, extending only partially thru the thickness of the tie plate C, to provide a horizontal shoulder 53 at the top of each recess 52, which lies immediately below the base flanges of the rail B, and is adapted to receive the locking extension 44 of the detent or pawl 25, when the spike is in locking position, to prevent withdrawal of the shank spike. At the opposite side of each opening from the recesses 52, the tie plate C is provided with a vertical slot 55 extending thru the thickness of the tie plate, and communicating with the opening 50, and these slots are adapted to receive the outer sides of the pawl 25, when in a collapsed non-locking position.

The member E used to move the detent into locking position consists of a narrow shank 60, having a head 61 thereon, the lower edge 62 of said shank being tapered from the outer side of the shank 62 towards the inner side thereof.

Referring to the application of the improved spike, the shank 10 thereof is driven into the opening 50; it of course being understood that the rail and tie plates have been properly placed upon the ties. The spike body is then driven until the head 11 engages the base flange of the rail B, and in this relation the pawl 25 at its lower portion will enter the fibers of the tie D, just inwardly of the upper surface thereof; the pawl not interfering to any great extent with the driving of the shank, due to the diagonal or inclined relation of the opposite edges 29 and 30 of the said pawl. When the shank 10 has been driven fully into the tie, the pawl moving member E is then in-

serted in the vertical slot 55 at the outer side of the spike, with the tapered lower edge 62 facing towards the downwardly extending projecting portion 41 of the pawl 25, and upon driving of the member E downwardly into the slot 55 and into the tie D, the pawl 25 will be forced from the outer side of the spike shank 10, laterally thru the opening 20, into projecting relation at its locking lug 44 beyond the inner surface of the shank 10, and into the recess 52, below the shoulder 53, in the relation of parts illustrated in Figure 1 of the drawing. The member E is driven fully into the slot 55 until the head 61 thereof rests on the bed plate or tie plate. When the parts are in this relation it is readily apparent that the shank of the spike cannot be withdrawn from the tie D, nor from the bed plate C, until the pawl 25 is collapsed thru the slot 20 out of locking relation below the shoulder 53 of the bed plate C. To effect this removal of the pawl from locking relation it is necessary to remove the member E, which may be readily done, by means of a tool inserted into the transverse groove 45 of the extension 41 of the pawl 25, and the pawl 25 rocked outwardly away from the rail, into the position illustrated in Figure 4, and it is thus readily apparent that the locking extension 44 may be removed from beneath the shoulder 53 of the bed plate.

Various changes in the shape, size, and arrangement of parts may be made to the form of invention herein shown and described, without departing from the spirit of the invention or the scope of the claims.

I claim:

1. In a spike the combination of an inserting shank having a head thereon, said shank below the head having a transverse slot therethrough from side to side, a pawl member pivoted at its lower end in the lower end of said slot, the pawl member above the pivot thereof being greater in width from side to side than the transverse dimension of the shank from side to side so as to permit the opposite sides of the pawl to extend outwardly of the opposite sides of the shank, and means formed with the shank to limit the degree to which the pawl may be collapsed or extended with respect to the opposite sides of said shank.

2. The combination with a rail including a base flange, a tie, and a bed plate between the tie and base flange of the rail, said plate having a transverse opening therethrough, of a spike including a shank insertable thru the bed plate opening into the tie and having a head thereon for rail base engagement, said shank having a transverse opening therethrough, a pawl movable in said opening of the shank and projectable at opposite sides of the shank, and means operable in

the opening of the tie plate for engagement with one side of the pawl at the outer side of the shank to drive the opposite side of the pawl into projecting relation beyond the inner side of the shank below said tie plate.

5. 3. The combination with a rail section adapted to rest upon ties, a bed plate having a transverse opening therein and being recessed upwardly from the bottom surface

10 thereof adjacent the opening to provide a substantially horizontal shoulder, of a spike including an inserting shank and a head adapted to engage the rail, said shank adapted to extend into the opening of the bed

15 plate into the tie, said shank having a transverse opening therethrough, a pawl movable in the transverse opening including a locking projection adapted to extend into the recess of the tie plate below said shoulder

20 of the tie plate, and means operable at the outer side of the shank in abutment against said pawl to force the locking projection thereof into locking relation with said shoulder of the tie plate.

25 4. The combination of a tie plate having a transverse opening therein, and a reduced slot communicating transversely with said transverse opening and extending thru the thickness of the tie plate, of a spike includ-

30 ing a head and a shank extending thru the opening of the tie plate, said shank having a transverse opening therein from side to side below said bed plate, a pawl operable in said opening of the shank having a lock-

35 ing extension adapted to project beyond the outer side of the shank below said plate, said pawl at the opposite side from the locking lug being adapted to project from the outer side of the shank when the locking lug is

40 in locking relation below the bed plate, and a pawl operating member movable in the reduced slot of the bed plate at the outer side of the shank for abutment against the pawl to drive the locking lug thereof into lock-

45 ing relation below the bed plate.

5. As an article of manufacture a spike comprising a shank having a transverse opening therethrough from side to side, said opening at a side of the spike being recessed

50 upwardly into the spike to provide a shoulder, and a pawl movable at its lower end in said opening having an upward grooved extension thereon for abutment against said shoulder, said pawl being greater in width

55 than the width of the slot transversely from side to side of the shank.

6. As an article of manufacture a spike having a lower tapered polygonal sided end, with straight guide ribs formed longitudinally of the spike along said tapered end at 60 diagonally opposed corners of the spike, the other corners being free of ribs or projections.

7. As an article of manufacture a polygonal shaped spike shank having a lower 65 chisel end formed by tapering opposite sides of the spike, said opposite sides of the chisel tapered end having ribs formed longitudinally of said shank decreasing in projecting relation from the chisel end of the shank upwardly, said ribs being only formed at two 70 diagonally opposed corners of the shank.

8. In a rail securing device the combination of a plate having a vertical opening therethrough, a spike adapted to be inserted 75 thru said opening, a pawl movably mounted in the shank of said spike, and of a width greater than the shank of the spike so that opposite portions of the pawl may extend beyond opposite sides of the shank of the 80 spike at the same time, and a lock member for insertion into the opening of the plate to engage against one side projecting portion of the pawl to force the other projecting portion of the pawl at the opposite side of 85 the shank of the spike outwardly beyond the spike shank.

9. In a railway spike the combination of a shank having a head thereon, a pawl member, means pivoting the pawl member adjacent its lower end on the spike shank, the pawl member above the pivot axis being of a width greater than the width of the shank so that opposite portions of the pawl above 90 the pivot axis may extend at the same time 95 beyond opposite sides of the shank.

10. In a railway spike the combination of a shank having a head thereon, a pawl member, means pivoting the pawl member adjacent its lower end on the spike shank, the pawl member above the pivot axis being of a width greater than the width of the shank so that it may be positioned to project at opposite sides of the shank at the same time, one of said projecting portions of the pawl 100 member having a notch inwardly from the upper edge thereof into which a tool may be inserted for moving the pawl member from a projecting relation at both sides of the shank to a projecting relation at only one 105 side.

ROCCO PRONINI.
